S. CURTIS TRUBEE, OF BROOKLYN, NEW YORK.

Letters Patent No. 99,263, dated January 25, 1870.

IMPROVEMENT IN WINDOW-BUTTONS.

The Schedule referred to in these Letters Patent and making part of the same.

To all whom it may concern:

Be it known that I, S. CURTIS TRUBEE, of Brooklyn, in the county of Kings, and State of New York, have invented certain Improvement in Window-Fastenings, of which the following is a specification, reference being had to the accompanying drawings.

My invention relates to devices for fastening windows; and

The invention consists in a notched button or latch, arranged to engage with and hold the ordinary fastening in position, and prevent it from being opened or unloosed by burglars, as hereinafter explained.

Figure 1 is a top plan view of an ordinary window-fastening, with my improvement applied thereto.

Figure 2 is a transverse vertical section, on the line *xx* of fig. 1.

In the drawings—

The parts A, B, and C, represent an ordinary window-fastening, which serves to lock the upper and lower sash together, and thus prevents them from being raised or lowered.

This device, being well known to the trade and the public, need not be further specially described.

In applying it to windows, the part A is secured to inner upper surface of the bottom rail of the upper sash, and the part B is secured to the upper surface of the top rail of the lower sash, the locking-lever C, when the parts are locked, standing at a right angle across the joint or crack between the rails of the two sash.

It is obvious, that when thus arranged, a knife-blade, or similar tool, can be inserted between the

sash, from the outside, and the lever C be thereby pushed to one side, thus unlocking the window. It is to provide a cheap and efficient means of preventing this that my invention is intended.

To accomplish this, I construct a simple button or latch, D, which has a hole in one end to receive a screw, *a*, by which it can be pivoted and secured upon the top rail of the inner sash, as represented in fig. 1.

This latch D has a notch, *e*, on its inner edge, near the opposite end, of proper size to receive and hold the outer end of the locking-lever C, the latch D being so located as to bring the notch *e* into proper position to engage with the lever C, when the latter is in position to lock the sash together, as represented in the drawings.

To release the lever C, it is only necessary to throw the latch D back, as represented in dotted lines in fig. 1.

This latch may be cast, complete, ready for use, without any finishing whatever, or it may be made as ornamental as desired. It is exceedingly simple, cheap, and efficient, and may be applied to the fastenings already in use.

Having thus described my invention,

What I claim, is—

The latch D, provided with the notch *e*, arranged to operate in connection with the locking-lever C, as herein shown and described.

S. CURTIS TRUBEE.
